UNITED STATES PATENT OFFICE.

HARRY C. GOODRICH, OF CHICAGO, ILLINOIS.

IMPROVEMENT IN TUCK-MARKERS FOR SEWING-MACHINES.

Specification forming part of Letters Patent No. 138,635, dated May 6, 1873; application filed October 5, 1872.

To all whom it may concern:

Be it known that I, HARRY C. GOODRICH, of the city of Chicago, in the county of Cook and State of Illinois, have invented certain new and useful Improvements in Tuck Markers for Sewing-Machines, of which the following is a full description, reference being had to the accompanying drawing making a part of this specification, in which—

Figure 1 is a plan; Figs. 2, 3, 4, and 5, details. Fig. 2 represents the device as seen from the point *x*; Fig. 3, the end as seen from the point *y*; and Fig. 4, as seen from *z*; and Fig. 6, a variation.

In the drawing, *A* represents a plate of sheet-metal with which the other parts are connected; *B*, sliding gage held in place by the thumb-screw *a*; *b*, slot to receive the thumb-screw by means of which the tucker is attached to the machine; *C*, spring-arm; *D*, spring-cloth-smoother, to which a portion of the creasing devices are secured; *e*, long tongue, which may be secured at the end and to the under side of *D*; *d*, tongue secured at the end and to the upper side of *D*, and curved upward, as shown in Fig. 3; *f*, slit cut in the plate *A*; and *e*, a part of the plate *a*, curved upward, as shown in Figs. 2 and 4. This part *e* may be made of a separate piece connected to *A*.

The relative position of the parts *c*, *d*, and *e* is represented in plan in Fig. 5, *d* being dotted in.

In use the cloth to be creased is passed over the tongue *e*, under *d*, then down under the tongue *c*, and, there being a little space vertically between *c* and the end of *e*, the spring-arm *C*, when brought down, will press down the tongue *d* upon the end of *e*, holding the cloth

at that point firmly between *d* and *e*; then, as the spring-arm descends still further, it will carry down *d* and *e*, and the cloth between *e* and *c* will be bent over into a very narrow fold, forming a well-defined crease.

The special office of *d* is to carry down *c* and keep the cloth down upon the plate *A* or the bed of the machine.

Where the bed of the machine is perfectly level it is not necessary to extend the plate *A* under the tongue *c*.

The parts *c*, *d*, and *e* should be made of steel or other suitable spring metal.

I make the tongues *c* and *d* as represented, but there are various ways in which *e*, or something which answers its purpose well, may be made, one form of which is represented in Fig. 6, in which *g* takes the place of *e*.

I prefer to make the marker substantially as at first described, rather than as shown in Fig. 6, because the tongue *e*, when located as described, has a greater tendency, as it descends, to fold the cloth over upon *c* than when made as shown in Fig. 6.

The form of the plate *A* and the cloth-smoother *D* is not essential; any piece of metal suitable to support the parts connected with *A* and *D* may be used.

What I claim as new is as follows:

The combination of the tongues *c*, *d* and spring-arm *D* with the lip or tongue *e*, plate *A*, and arm or hammer *C*, all operating substantially as and for the purposes specified.

H. C. GOODRICH.
